H. A. WALKER, JR.

DUST COLLECTOR

Filed April 30, 1924

UNITED STATES PATENT OFFICE.

HOBART A. WALKER, JR., OF MAPLEWOOD, NEW JERSEY.

DUST COLLECTOR.

Application filed April 30, 1924. Serial No. 710,095.

To all whom it may concern:

Be it known that I, HOBART A. WALKER, Jr., a citizen of the United States, and a resident of Maplewood, in the county of Essex 5 and State of New Jersey, have invented certain new and useful Improvements in Dust Collectors, of which the following is a specification.

This invention relates to a dust collector 10 for use with coal-burning furnaces, etc., and comprises an improved device of this class adapted to be used in connection with any device to receive ashes when removed from the furnace and to permit the 15 handling of ashes without the usual accompaniment of dust in the furnace room. The device herein is, without change of any kind, adapted for use with any type of furnace or range using coal as a fuel.

An important object of the invention is 20 the provision of a sanitary, self-contained device which is not permanently attached to the furnace or ash receptacle but which may be easily positioned for use in connection therewith without making any change in either.

A feature of the invention relates to the 25 construction of the hood which is adapted to effect circulation of dust therein to collect the dust and expedite its removal therefrom by utilization of the furnace draft.

Other features relate to the construction 30 of the dust-collecting hood which adapt it for use with any furnace or ash receptacle, without change or addition thereto, or for changing the position of the ash receptacle relatively to the furnace.

These and other features of the invention 35 not hereinbefore referred to will be herein-after described and claimed and are illustrated in the accompanying drawing, in which:

Figure 1 is an elevation, partly in section, 40 of an ash receptacle provided with a dust collector embodying the invention, it being shown in operative relation to a coal-burning furnace, and

Fig. 2 is a section thereof taken on the line 2—2, Fig. 1.

Referring to the drawings, 2 designates 45 a furnace in conventional form adapted for burning coal, the coaling door of which is designated by 3 and the coaling opening by 4, while the ash-pit door and opening 50 are designated by 5 and 6, respectively. I have shown an ash receptacle or can 7, upon

which is positioned a collecting hood 8, said hood being formed with a flange 9 at the bottom thereof to permit the hood to be used with cans of different diameters. 60 Handles 10 are provided on the hood 8 to facilitate the removal of said hood from the can for emptying, etc. At 11 is shown an opening in the hood 8 adapted to permit entrance of ashes to the receptacle, a lip 12 65 being shown surrounding said opening. An opening 13 is shown in the collecting hood 8, which is provided with a flange 14 adapted to receive one end 15 of a pipe whose other end 16 is adapted for insertion 70 into the coaling opening 4 of the furnace. The pipe is shown herein as comprising the elbows 17 and 18 and an intermediate straight length 19. It will be seen that by this arrangement of the pipes the ash receptacle may be placed on either side of the 75 furnace, the pipe as a whole being reversible in position to meet the requirements of this change of position.

The openings 11 and 13 are located, preferably, near the lower edge of the hood 8 in order that the dust rising from the ashes deposited in the receptacle may be caused to circulate or collect in the relatively large upper portion of said hood, partly falling 85 back into the receptacle 7 and partly removed by the draft through the pipe 17—19—18 and carried to the furnace opening 4, the usual flue draft of the furnace then causing such dust to be drawn thereinto to 90 pass up said flue and to the outside air.

While I have shown the pipe 17—18—19 as made up of ordinary stove-pipe sections and elbows, it will be apparent that piping of any other description and of any desired cross section may be employed to accomplish the purposes of the present invention. And although I have shown a preferred location for the opening for the pipe 17—18—19, namely, at the side of the 100 hood 8 opposite the ash-receiving opening 11, said pipe opening may be located at any other portion of the hood.

In operation, a can 7, of any ordinary diameter, will be located alongside the furnace, in position to receive the pipe 17—18—19, the hood 8 will be positioned on the can 7, the flange 9 of said hood resting on the upper rim of the can. The end 15 of the pipe section will then be fitted over the flange 14 while the other extreme end of the pipe 17—18—19 will be placed on the lower 105 110

edge of the opening 4 for the coaling door. Ashes from the ash-pit may then be shoveled through the opening 6 of the ash-pit and into the opening 11 in the hood 8. The draft in said hood 8 caused by the direct draft from the furnace flue through the furnace and pipe 17-18-19 will cause all dust arising from the ashes to be first drawn upward and circulated in the upper and central parts of the hood 8 and such parts thereof as do not fall back into the receptacle to be sucked from said hood into the pipe 17-18-19 and the furnace flue to the outside of the furnace room, instead of spreading and settling in the room and on all articles therein, as has heretofore been the case.

As many changes could be made in the above construction and many apparently widely different embodiments of my invention designed without departing from the scope of the appended claims, I intend that all matter contained in the above description or shown in the accompanying drawings shall be interpreted as illustrative merely of an operative embodiment of my invention and not in a limiting sense.

What I claim is:—

1. A dust collector adapted for use with an ash receptacle, comprising a removable hood therefor provided with an ash-receiving

door, an outlet opening in said hood, and a dust-conducting pipe leading from said opening to the interior of the furnace, said hood having a relatively large upper portion extending above said door and opening providing a chamber adapted to cause the dust to circulate and collect in said upper portion and to fall in part into the receptacle, the residue being drawn into the dust-conducting pipe and out through the furnace flue.

2. A dust collector adapted for use with an ash receptacle, comprising a removable hood having a cylindrical side wall with a closed top and provided with an ash-receiving door and outlet opening located opposite thereto in said side wall, and a dust-conducting pipe leading from said opening to the interior of the furnace, said hood having a relatively large upper portion extending above said door and opening providing a chamber adapted to cause the dust to circulate and collect in said upper portion and to fall in part into the receptacle, the residue being drawn into the dust-conducting pipe and out through the furnace flue.

Signed at Maplewood, in the county of Essex, and State of New Jersey, the 26 day of April, A. D. 1924.

HOBART A. WALKER, JR.
